No. 876,955.

PATENTED JAN. 21, 1908.

R. S. FEICHT,
DYNAMO ELECTRIC MACHINE,
APPLICATION FILED OCT. 3, 1905.

UNITED STATES PATENT OFFICE.

RUSSELL S. FEICHT, OF PITTSBURG, PENNSYLVANIA, ASSIGNOR TO WESTINGHOUSE ELECTRIC & MANUFACTURING COMPANY, A CORPORATION OF PENNSYLVANIA.

DYNAMO-ELECTRIC MACHINE.

No. 876,955.

Specification of Letters Patent.

Patented Jan. 21, 1908.

Application filed October 2, 1905. Serial No. 281,187.

To all whom it may concern:

Be it known that I, RUSSELL S. FEICHT, a citizen of the United States, and a resident of Pittsburgh, in the county of Allegheny and State of Pennsylvania, have invented a new and useful Improvement in Dynamo-Electric Machines, of which the following is a specification.

My invention relates to conducting end rings or similar parts for dynamo-electric machines, and has special reference to such ring members as are adapted for use with the rotatable secondary members of induction motors.

The object of my invention is to provide suitable resistance rings for induction motors or similar machines that may be easily applied and that shall embody a specially ventilated construction.

Squirrel-cage rotors or secondary members of induction motors are usually provided with a plurality of conducting bars near their outer cylindrical surfaces which are connected at or near their extremities by suitable resistance conductors. In the prior art, the resistance conductors have assumed various forms, such as rings which were bolted or otherwise attached to the ends of the bars or wires which projected from the ends of the core slots, and it often occurred, particularly in machines that were subjected to adverse conditions, such as relatively large slips or high speeds, involving considerable secondary losses or the use of rings of small diameters, that the temperature of the rings rose to excessive values. In order to obviate this difficulty, I have provided a ventilated end ring construction which may be used in connection with air-propellers to adequately radiate the heat generated and may comprise, in general, a plurality of conducting ring members which are either separate units or are so interconnected by segmental webs that a large radiating surface is provided.

Obviously, my invention is not dependent upon a specific means for attaching the end conductors to the bars, but may embody any one of such suitable devices as may be known in the art.

My invention is illustrated in the accompanying drawings, in which

Figure 1 is a sectional elevation of a por-

tion of the rotor of a dynamo-electric machine which is provided with end rings constructed in accordance with my invention. 55 Fig. 2 is an end elevation of a portion of the machine disclosed in Fig. 1, and Fig. 3 is a view similar to Fig. 1, of a modified form of end ring having air-propelling vanes.

Referring to the drawings, a cylindrical 60 core portion 1 of a dynamo-electric machine is provided with a plurality of conducting bars 2 near its outer cylindrical surface, and a pair of similar end rings 3 to which the bars 2 are bolted near their extremities. The end 65 rings 3 comprise similar body portions which are divided into annular sections 5, 6 and 7 by circumferential grooves 8 and 9, the several sections being connected together by equally disposed segmental webs 10. The 70 sections 7 of the rings 3 are provided with annular projections 11 which extend inwardly and through which the rings are supported from the core by a plurality of equally disposed clamping bolts 12. The clamping 75 bolts 12 are provided with similar spacing collars 13, which are interposed between the projections 11 on the rings 7 and the end rings or plates 1^a of the core 1 into which the bolts are tapped. 80

Referring particularly to Fig. 1, air-propelling vanes 14 are bolted to the ends of the core frame or spider 1^b and serve to create a circulation of air through the grooves 8 and 9, since the core member to which they 85 are attached rotates at a relatively high speed in operation. The ring member comprising the portions 5, 6 and 7 may be divided into two members or completely segregated into three rings by extending one or 90 both of the slots 8 and 9, and the inner ring portion 7 may or may not be supported from the frame 1^b.

Fig. 3 shows a modified form of ventilated end ring, in which three ring portions are independently supported by the conducting bars to which they are bolted. An air-propeller, comprising a set of vanes 15, extends inwardly from the cylindrical surface of the ring and is attached thereto by bolts 16. 95 100

The air-propeller vanes are not essential parts of my invention, and it will be readily seen that many modifications in the structure and arrangement of parts may be made

without departing from the spirit of my invention, and I desire that such variations shall be included within its scope.

I claim as my invention:

5 1. An end ring for dynamo-electric machines comprising a plurality of annular portions connected by segmental webs.

10 2. In a dynamo-electric machine, the combination with a cylindrical core member and a plurality of longitudinally-disposed conducting bars therefor, of a conducting end ring to which said bars are attached, said ring comprising a plurality of portions connected by segmental webs, and one of said 15 portions having an annular flange that extends inwardly and is bolted to the core member.

20 3. In a dynamo-electric machine, the combination with a rotatable core member, a plurality of conducting bars disposed in a plurality of longitudinal slots near the sur-

face thereof, and a plurality of end rings of conducting material fastened to said conducting bars and separated by circumferential slots, of a set of air-propelling vanes 25 attached to said rotatable member and located inside the inner walls of said ring.

4. In a dynamo-electric machine, a rotatable member comprising a plurality of conducting bars, end-connecting rings of conducting material separated by circumferential slots, and a set of air-propelling vanes attached to said rotatable member inside the inner diameter of said rings.

In testimony whereof, I have hereunto 35 subscribed my name this 30th day of September, 1905.

RUSSELL S. FEICHT.
